MECHANISM FOR DELIVERING PULVERIZED MATERIAL

Henry G. Lykken, Minneapolis, Minn.

Application August 31, 1938, Serial No. 227,670

3 Claims. (Cl. 83—11)

My invention relates to a new and improved method of and mechanism for delivering pulverized material classified to a selected particle size. In such machines, exact and efficient classification implies the removal of all particle sizes below a given size, with no oversize particles in the finished product.

In the following disclosures there is shown, among other things, a mill in which both a pulverizing action and a classifying action are accomplished in the same chamber. The pulverizing action takes place by means of a rotor created pulverizing air vortex such as is described in my Patent No. 1,838,560 issued December 29, 1931, but, as is well understood, such a vortex can be created by currents of air projected tangentially (non-radially) into a chamber, as covered by my Patents No. 1,768,621 issued July 1, 1930, and No. 1,756,254 issued April 29, 1930. As the description proceeds it will be apparent that the principles of and mechanism for classification can be used separately from, or in conjunction with any type of pulverizing machine, and may or may not be a part of that machine. Where "air" is referred to in this specification it will be understood that the term is used generically to include other gaseous media that may be found useful in the particular case of pulverization and classification.

Heretofore, there have been proposed a wide variety of methods of classifying pulverized material, including simple sorting devices depending upon the carrying capacity of an air stream, centrifuges, multiple chambers, screens, etc. In such prior classification devices, substantial quantities of finished product, i. e., material pulverized to the desired size, has been returned to the pulverizing apparatus along with the oversize material rejected in the classifier. This amounts to not only inefficient classification insofar as decreased output for the machine is concerned, but even a small percentage of such finished product, including "fines," returned to the pulverizer will greatly reduce the efficiency of the pulverizer (as much as fifty percent) because such material "cushions," retards and interferes with the pulverizing action upon the material yet to be reduced. The sufficiently reduced material that failed to be removed in the classifier is carried off in several different forms, that is, it may be clinging to an oversize particle, several finished particles may be clustered together making a larger mass, the particles may reach the outer wall of the chamber and be gathered up by a group of oversize returns, etc.

It is, broadly, an object of this invention to remove in the classifier practically all of the material that is sufficiently pulverized so that only material actually requiring further reduction in size is rejected and returned to the pulverizing chamber, while all the finished product is delivered to whatever collection system that is connected to the classifier.

10 A further serious defect with existing types of classifiers is that while the mechanism may be adjusted to deliver from the machine a selected maximum particle size the classifier will nevertheless permit larger particles to pass out with the finished product and in many cases this is unsatisfactory even commercially.

Again, the conditions for the return of oversize particles from the classifier for further pulverization have been such that the material is returned intermittently thus imposing intermittent loads upon the pulverizer.

It is also, broadly, another object of this invention to overcome the foregoing as well as other defects interfering with higher efficiency of the mechanism.

20 25 Also in prior devices depending upon air in the classification, the drag of the outgoing air on the material is generally at a right angle to the centrifugal or other force participating in the classification action.

Also in prior devices depending upon air in the classification, the drag of the outgoing air on the material is generally at a right angle to the centrifugal or other force participating in the classification action.

30 35 A further object of this invention is to subject the pulverized material particles which are introduced into the classifier chamber to the drag of an outgoing current of air, carrying the particles of desired size, and to an opposing centrifugal force.

Still further objects of this invention are to subject the material which is introduced into the classifier chamber while suspended in air to the whirling action of a vortex, to the pulsating action of a closed-end rotor, to increasing centrifugal force as the size of the oversize particles to be rejected is reduced, and removing the finished product from the center of the vortex or of the rotor as rapidly as the same is separated from the oversize material.

Still other objects of my invention comprise subjecting the material in the classifier to a continuous scavenging with large quantities of air; and allowing the entering stream of air and 40 45 suspended material to promptly expand at the beginning of the classifier action; and aerating the rejected oversize material immediately before it leaves the classifier.

Even other objects of this invention consist 50 55 in providing a unitary pulverizing and classifying

ing machine in one chamber so arranged that the material being pulverized is subjected to two different vortex actions, is continually and promptly scavenged with large amounts of air, in both the pulverizer chamber and in the classifier chamber, the oversize material rejected in the classifier is returned to the pulverizing chamber continuously for further reduction without causing intermittent loading of the pulverizing chamber, and the returned oversize is subjected to a specially imparted downward component.

Other and further objects of this invention will be understood by those skilled in this art from this specification taken with the accompanying drawings, wherein—

Figure 1 is a vertical central section of a machine embodying the above mentioned principles;

Fig. 2 is a cross-section substantially on the line 2—2 of Fig. 1, with parts broken away to facilitate the illustration;

Fig. 3 is a fragmentary sectional view of a modified structure; and

Fig. 4 is a vertical central section of a classifier apart from any pulverizing mechanism.

Referring to Figs. 1 and 2, in the embodiment chosen to illustrate the principles of this invention, the combined pulverizer and classifier comprises a cylindrical shell 11 supported upon a base 12 and closed at the top by a plate 13. The material to be pulverized may be fed into the casing from a hopper 14 by means of a feed screw 15 working in the sleeve 16 and opening into the casing as indicated at 17. The feed screw is driven from a motor 18 through variable speed reduction gearing enclosed in the housing 19, and which may be of any suitable type, and may or may not be supplemented by a chain and sprocket drive 19A. Obviously, other forms of feeding mechanisms may be used.

In the embodiment illustrated, a pulverizing air vortex is set up by the closed-end rotor, indicated generally at 21, and comprising a hub 22, top and bottom plates 23 and 24 and a plurality of spaced apart radial plates 25. The number of blades and the spacing thereof around the rotor will be governed by the pulverization requirements, and the desirability of maintaining a pulverizing air vortex peripherally of the rotor. The rotor hub is mounted upon the shaft 26 which is supported by suitable bearings in the top 13 and bottom 12 of the machine, the shaft being driven by a motor or other source of power (not shown) and in any appropriate manner for the speed required. The area of the casing 11 in which the rotor 21 operates is known as the pulverizing chamber or zone, and is indicated generally by the arrow 27. The pulverizing chamber is closed at the bottom by the dished plate 28 having a central opening 29.

The plate 28 is spaced a substantial distance above the bottom 12 of the mill and in that lower portion of the casing 11 is a large opening 30 through which air is admitted to the space 31, and from there into the mill through the opening 29. The latter opening may be covered by a slideable shutter 32 to regulate the amount of air admitted into the pulverizing chamber as one means of control thereof. It may be said that with the machine as here shown and the principles set forth in this application large quantities of air are used and in fact the volume of air is considerably increased over the volume of air heretofore used with similar types of combined pulverizing and classifying machines.

Air is admitted to the pulverizing chamber beneath the bottom plate 24 of the rotor, and all around the periphery of the rotor. The entry of the air to the chamber 27 is facilitated by a plurality of fan blades 33 that are mounted on the underside of the bottom plate 24 of the rotor, as shown. The number of these blades will vary, as will be understood. It will be noted that these fan blades are shaped to cooperate with the contour of the bottom plate 28 and that there is but a narrow opening 34 for the air as it enters the chamber 27. This arrangement likewise provides an air seal against material in the pulverizing chamber 27 getting beneath the bottom plate 24 of the rotor.

The air admitted to the chamber 27 is caused to whirl in a violent, high speed vortex by the rotor 21, and the material fed into the chamber through the opening 17 is picked up and carried in this air vortex. The material is therefore subjected to the centrifugal forces of the vortex, the particles smash into each other with great force and rub against each other as they rotate in the vortex. Under these violent impacts and attritions the particles are reduced in size. Of course as the sizes of the particles change the effect of centrifugal force thereon varies and the newly created particles seek other strata-like positions, thus causing further collisions and rubbings, and so on until the material is reduced in size adequately.

In the mill as illustrated the pulverizing chamber 27 is shown as provided with a corrugated lining 35 the use of which is optional to facilitate the formation of a bed of material upon the wall of the pulverizing zone so that additional pulverization occurs at the wall of the chamber by material striking the material held there, rather than dry material striking the walls of the chamber. Some bed of material will be formed under most conditions, and its depth will be increased by the use of the corrugated lining.

Also in the mill as illustrated it is noted that the pulverizing rotor 21 is larger in diameter at the bottom than at the top so that the rotor tapers inwardly at the top of the mill. This construction has been found of advantage when pulverizing some of the heavier materials, and for other reasons. However, it will be understood that the pulverizing vortex could be created by a rotor which is not tapered at all, or which is tapered in the opposite direction, depending upon the desires of the mill designer and the problems encountered in connection with a particular material or requirement.

Of course the air vortex need not be set up by a rotor at all but may be created by any other suitable means such as high pressure air, super-heated steam, etc., appropriately directed into the chamber to set up the pulverizing vortex.

Efficient action of the pulverizing mechanism requires thorough and complete scavenging of the material being pulverized, preferably by a cross-current of air, to constantly remove from the entire pulverizing zone all material which is sufficiently reduced in size, and as fast as the same is so reduced. Such finished material must be quickly gotten out of the pulverizing zone and kept out because such material merely serves to "cushion" or interfere with the pulverizing action upon the insufficiently reduced material. In the mill illustrated such action is obtained by the vertically rising column of air continually admitted to the pulverizing chamber at its bottom, and in sufficient quantities, and the finished pul-

verized product suspended in the air, passes out of the pulverizing chamber at the top. I prefer to remove from the pulverizing zone even a substantial quantity of oversized or insufficiently reduced material so as to be sure to remove all of the finished material as promptly as possible. Of course the oversize material must be separated from the finished material and returned to the pulverizing zone for further pulverization while the finished product should be removed from the mill. That is the function of the new and improved classifier about to be described.

The portion of the casing 11 immediately above the pulverizing chamber 27 may be termed the classification chamber and is indicated generally at 41. The upper portion of the classification chamber is closed partially by the flat ring 42 which is supported upon the annular shoulder 43. In the classification chamber is a rotor indicated generally at 44 and comprising a central hub 45, mounted upon shaft 26 and carrying a plurality of radial blades 46. At the top, the outer edges of the rotor blades 46 are fastened to an annular angle iron 47 to which is attached the laterally extending, ring-shaped, stop plate 48. In the embodiment shown in this figure, the outer edges of the rotor blades are tapered inwardly and downwardly from the ring 47, as indicated at 49 on the drawings, so that each blade of this classification rotor is very narrow at the bottom of the rotor and of substantial width at the upper end, producing a rotor which has a large diameter at the top and is progressively smaller in diameter to the bottom thereof. The classifier rotor also sets up an annular vortex action in chamber 41, but usually this vortex will have speeds of a much lower order than the speeds of the pulverizing vortex.

Before describing the classifier action, the arrangement for withdrawing air and final material from the classifier chamber 41 will be described.

The opening 51 in the ring 42 is disposed close to and axially of the classification rotor 44 and constitutes the outlet from the classification chamber 41 into the upper chamber 52 of the mill. The latter chamber may be described as the outlet chamber, and has the discharge duct 53 (Fig. 2) of the mill communicating therewith. (This duct preferably connects with a suitable collection system, not shown). In the embodiment shown in the drawings the chamber 52 has a fan 54 located therein, the purpose of which is to continuously draw from the classification chamber 41 and into the outlet chamber 52 the air and finished material. The fan shown comprises a hub 55 mounted upon the shaft 26, which hub terminates in the flat disk 56. A ring-shaped plate 57 is appropriately secured to the disk and to the bottom of that plate are secured a plurality of fan blades 58 which are very narrow and do not extend down beyond the depth of the disk 56. It will be understood of course that any other construction of suction fan, centrifugal or otherwise, may be used in place of the fan that has been described, and also the fan need not be located in the mill at all but may be an entirely separate element, where used.

The suction action of the fan is effective throughout the entire mill. Accordingly, the finished material is being constantly withdrawn inwardly from the vortex throughout the height of the chamber 41, through the rotor and along 75

the shaft 26, or the axis of the vortex as it may be termed, into the opening 51. Thus, the intake of the rotor 44 is from its periphery, and its discharge is from its axis.

As has been described, the material discharged from the pulverization zone contains a considerable quantity of oversize material as well as the finished material, and is rotating in a rapid but confined vortex. By the arrangement of the classification rotor as shown and described this vortex is permitted to immediately expand in the bottom of the classification zone, and the vortex is at once substantially reduced in speed. Such an immediate expansion also at once spreads the material and subjects it to the scavenging action of the air being continually drawn through the mill so that particles that have been sufficiently reduced in size tend at once to be carried toward the hub of the rotor and out of the mill. It will be understood of course that not nearly all of the finished product is immediately removed from the classification chamber. A very substantial part of it remains yet to be classified and that action occurs under the influence of the classification rotor 44 which is designed to continue the vortex of reduced speed and to subject the material in that vortex to repeated "sorting" actions, or pneumatic "sifting" actions.

That is to say, as each rotor blade advances in the direction of rotation there is a suction created behind the blade which draws air and material toward the center of the rotor, and as the rotor advances there is pressure created by the advancing face of the following blade which forces the air and material out of the rotor. Accordingly the material in the vortex goes in and out of the rotor around the several blades as the rotor rotates and this constant pulsating action causes the material to spread out and to approach the center of the rotor so that the air leaving the chamber through the opening 51 will carry with it the finished product. The particles that are thrown out by the rotor are subjected to centrifugal force which, of course, acts upon a particle according to its mass. This force opposes the force or drag of the air carrying the particle out of the chamber, and the proportioning of these forces determines the selected particle size.

In the present machine, the gradually increasing width of the rotor blades toward the top of the machine increases the centrifugal force exerted by the rotor blade. Accordingly the material that travels upwardly in the classification chamber 41 which is near, but yet above the desired particle size will have added centrifugal force imparted to it to keep it out of the outlet opening, and force it to the wall of the chamber from where it will be returned to the pulverizing chamber. The repeated pulsations of the material by the rotor blades frees all material that has been sufficiently reduced in size, and rejects all oversize material.

The oversize material is thrown to the outer wall of the chamber 41. It has been found that even with appropriate precautions it is not, as a practical matter, possible to prevent particles which are a proper size from reaching the outer wall of the classification chamber 41 and there be mixed with the oversized material. To free all such material I provide means to create a turbulence in the material on and near the wall of the casing 11 and before it leaves the classifier. Hence any particles which are of a proper size

will be freed from the oversize and work inwardly, finally escaping through the discharge outlet 51.

In the illustrated embodiment, the lower portion of the wall of the classification chamber 41 is provided with corrugations 61. It will be noted that these corrugations are inclined downwardly in the direction of rotation of the vortex. The oversize material that is thrown outwardly in the classifier vortex reaches the wall of the chamber and slides down the same, both that above the corrugations as well as that opposite the corrugations. Accordingly the incline of the corrugations in the direction of rotation of the vortex gives a downward component to the returning material so that the vortex is in fact aiding the return of the oversize material to the pulverizing chamber. This return action goes on continuously, and together with the reduced vortex at the bottom of the classifier chamber, there is no accumulation of the oversize material there, and no periodic loading of the pulverizing rotor. At the same time the action of the air in the corrugations providing a disturbing turbulence in the air and material there permits the rising spiral of air in the vortex to free any finer material which may be mingled with the oversize.

Again these inclined corrugations also serve to push away from the wall and out in the vortex the material that is descending along the wall from above the corrugations 61.

As seen from Fig. 2, the corrugations 61 are wider than the corrugations 35 in the pulverizing chamber 21, thereby projecting further out into the mill, and also are spaced on much wider centers. In one mill, the corrugations in the pulverizing chamber have been one-half inch deep and spaced on about one inch centers, while the corrugations in the classifier chamber have been approximately one inch deep and spaced on between three and four inch centers, with an inclination of thirty degrees, following of course the contour of the wall. These spacings will vary from mill to mill according to the requirements for each and it will be apparent that different lengths of corrugations may be used, depending upon the particular conditions in the classifier, while under certain circumstances the corrugations may be vertical.

It should be pointed out that there is no definite relationship between the number of blades on the pulverizing rotor 21 and the number of blades upon the classifier rotor 44. The two rotors act independently of each other, and in each case the number of rotor blades, size, shape and spacing is chosen by the designer in accordance with the particular pulverizing or classifying problem with which he is faced. Materials vary in weights, in degrees of hardness or friability, and the requirements of users vary as to the top particle size desired. These and other factors determine what will be the construction of the respective rotors.

It also may be pointed out that the ring 48 cooperates with the ring 42 to constitute a running seal to prevent the discharge of material between the rings and to the opening 51.

With the construction and arrangement of parts which have been illustrated and described it has been found that the parts, the volume of air, etc. can be proportioned and balanced so that any particle size can be selected as the top particle size. And it has further been found that with the described mechanism removal from the pulverizing chamber of sufficiently reduced material is so rapid that there is a substantial reduction 75

in the number of "fines" in the finished product so that the large majority of particles ultimately collected are very close to the selected top size. For example with the mechanism adjusted for a 15 micron top size most of the particles will be within the range of 10 to 15 microns. The same ratio holds even for sizes below 15 micron top size.

It will be appreciated that the mechanism is readily adaptable to the handling of different materials and even different particle sizes of the same material by changes in the volume of air, by changes in the suction fan, and by simple changes in the rotors to vary the number of blades or the contour of the blades, including using straight blades or those curved either in the direction of rotation or in the opposite direction. The size of the outlet opening 51 can be readily changed by replacing the ring 42 with another having a different sized opening. In place of varying the air opening by means of the slide 32, the outlet duct 53 from the machine to the collection system may be controlled by means of a damper indicated at 50.

Other modifications are illustrated in the further figures of the drawings, now to be described.

Figure 3 illustrates a modified form of classifier rotor in which the rotor 91 has an upper portion 92 which is of uniform diameter, and below which is an inwardly and downwardly tapered portion 93. Around the outer edges of the portion 92 of the rotor blades is a large mesh screen 94. The mesh of this screen may be two or three openings to the inch.

While it has not been illustrated, I have found that flat, spaced apart, ring-shaped plates or wire bands or hoops may be substituted for the screen and with equivalent operating effect, which has been found desirable with some materials and in some instances.

The purpose of the screen or other arrangement is to introduce a certain interference with the normal in and out flow of air and material caused by the rotor blades and to thus modify to some extent the pulsating action laterally. Thus the passage of the particles through the classifier zone and out of the chamber will be retarded sufficiently to complete the rejection of undesired oversize particles.

Of course, the part of the rotor of uniform diameter could be of different proportions and height than those illustrated in Fig. 3 by way of example.

Figure 4 illustrates a classifier that is separate and apart from the pulverizer. In this case the material enters the casing 71 through pipe 72 in the direction of a vortex in the casing. The material may be suspended in air, or not, as suits the individual case. Air also may be introduced into the classifier chamber through the lower opening 73, below the rotating plate 74, and on the bottom of which are a plurality of fan blades 75. The classifier rotor 76 creates and maintains a vortex of air and suspended material in the chamber 71. In this case there is shown a design of rotor which is somewhat like that shown in Fig. 3 in that the rotor comprises a central hub 76 carrying a plurality of radial blades 77, the upper portion of which, to the point 81, is of uniform diameter and then the blades taper downwardly and inwardly as indicated at 82. At the upper ends the blades carry the annular angle iron 78 to which is fastened the stop ring plate 79.

The operation of the classifier of Fig. 4 is sub-

stantially the same as that described in connection with the classifier of Fig. 1. The finished product is discharged from the mill through the central opening 83 formed by the ring-shaped plate 84 which divides the classifier chamber from the outlet chamber 85 in which there is shown a suction fan 86 that also discharges the material through an outlet 87. The fan 86 and the rotor 76 and the plate 74 are all mounted upon a shaft 88 supported in appropriate bearings in the top and bottom plates of the mill, the shaft being driven by any suitable source of power (not shown).

The rejected oversize material passes from the mill through one or more outlets 89 located at the bottom of the classifier opposite the air inlet. Thus, even the rejected oversize is subjected to a final aeration or scavenging action to release any particles that have been sufficiently reduced and which may be among the oversize particles.

Of course it will be apparent that the described mechanisms may be used to classify into two or several classes of particle sizes, as well as the operation described in this specification.

The types of rotors shown have been found to be particularly useful when classifying material to very small particle sizes, for example, less than five microns and in classifying lightweight materials, as well as with other materials and larger particle sizes. The number of blades and the spacing thereof are chosen to suit the particular conditions.

While all the rotors that have been described have had a tapered portion, it is practical and satisfactory to, in some instances, have rotor blades for the classifier which are of uniform width and in such cases the blades also may be surrounded by the wire or similar arrangements, if desired.

With devices such as have been hereinabove described, I have successfully pulverized and classified numerous materials on a commercial scale. With a classifier chamber twenty-four inches in diameter containing a rotor of fifteen inches maximum diameter rotating at 2600 R. P. M. crystalline calcite has been pulverized and classified to a top size of twenty-five microns at the rate of two hundred fifty pounds per hour. By increasing the rotative speed the maximum particle size delivered was five microns. Increasing the height of the classifier has enabled the obtaining of a maximum particle size less than five microns. Likewise increase in fineness of delivered particles has been obtained by other variations in the classifier rotor such as the diameter, or the shape and number of the blades, and by adding the screen or disks to the rotor as heretofore described.

Modifications in the arrangement and location of parts may be made within the spirit and

scope of my invention and such modifications are intended to be covered by the appended claims.

I claim:

1. A machine for delivering material of a selected maximum particle size which comprises a casing having a bottom and a top, means for admitting air through the bottom of the casing, a rotor mounted for rotation in the casing, means for operating the rotor so as to set up and maintain in the casing about the rotor an intense, high-speed, pulverizing vortex of air and suspended material, means for feeding material to the casing and vortex, means for withdrawing air and pulverized material from the vortex at the upper end of the rotor and into a classifying chamber, a rotor mounted for rotation in the latter chamber, the rotor being tapered outwardly and upwardly from adjacent the pulverizing rotor to the upper end of the chamber and arranged so as to set up and maintain in the chamber a less intense vortex and to subject the pulverized material therein to repeated lateral movements back and forth as the same spirals upwardly in said casing, and an outlet for selected material and air located axially in the end of the rotor near the upper end of the casing.
2. A machine for segregating particles of pulverized material comprising a chamber having an axial outlet at one end thereof, means for feeding material and air into the chamber, a rotor mounted in the chamber and causing the air and material to whirl in a vortex in which the material is suspended in the air, the rotor having an end plate adjacent the outlet and a plurality of spaced apart radial blades extending from the axis of the rotor and a major part of the height of said chamber below said outlet, the rotor end plate having an opening therein registering with said outlet, the suspended material moving inwardly and outwardly of the rotor repeatedly as the same spirals through the casing toward the outlet, and means for continuously removing the selected material through said outlet and opening.
3. In a machine for delivering pulverized material of a selected maximum particle size, a casing, a bladed rotor mounted therein of less diameter than the casing and of substantially a corresponding length, the rotor also being of substantially less diameter at one end and tapering toward the opposite end, means for feeding air and suspended material into said casing near the smaller end of said rotor and into the space around said rotor, a plate closing the larger end of said rotor except for an outlet for selected material in the central portion thereof, and means for drawing air and selected material through said outlet.

HENRY G. LYKKEN.
